C. H. WILLIAMS.
SAFETY GUARD FOR BRAKE BEAMS.
APPLICATION FILED JULY 3, 1917.

1,287,159.

Patented Dec. 10, 1918.

Inventor

Charles Haines Williams

By *J. M. Agnew, Atty*

CONCEIVED & DRAWN BY PATENT OFFICE

CHARLES MAXIMUS WILHELM, OF CHICAGO, ILLINOIS, ASSIGNEE TO CHICAGO RAILWAY EQUIPMENT COMPANY, OF CHICAGO, ILLINOIS, A CORPORATION OF ILLINOIS.

SAFETY-GUARD FOR BRAKE-BEAMS.

Specification of Letters Patent Patented Dec. 10, 1918.

1,000,450.

Application filed July 8, 1917. Serial No. 172,637.

To all whom it may concern:

Be it known that I, CHARLES WILHELM, a citizen of the United States, residing at the city of Chicago, county of Cook, and State of Illinois, have invented a certain new and useful Improvement in Safety-Guards for Brake-Beams, of which the following is a full, clear, and exact description, such as will enable others skilled in the art to which it appertains to make and use the same, reference being had to the accompanying drawings, forming part of this specification.

This invention relates generally to railway rolling stock, and specifically to certain improvements in brake rigging for trucks.

The object of the invention is to provide a safety arrangement which may be incorporated in a variety of conventional truck structures and which will operate to prevent the brake beam climbing or being displaced upwardly, as by the friction of the wheels, in the event of the detachment of the brake beam hangers.

As ancillary objects, my invention contemplates the provision of such a safety device in conjunction with the guiding arrangement known as the third or fourth point support, of the type illustrated in my United States Letters Patent No. 997,868, dated July 11, 1911, as well as the construction and disposal of the safety device in such manner as to assist in the throwing off of the brake shoes from the wheels upon the release of the brakes.

Other objects of the invention will be obvious or pointed out hereinafter, reference being made to the accompanying drawings in which various illustrative forms are shown, and in which—

Figure 1 represents a detail of a truck in which the parts constituting my invention are shown in side section, and other transversely extending portions of the truck equipment are shown in vertical section;

Fig. 2 represents a similar detail but showing a modified form;

Fig. 3 represents a similar detail but showing a different disposal and form of the invention;

Fig. 4 represents a similar detail of a third modified form.

Referring to these illustrations in detail by means of the reference numerals ap-

piled, let it be understood that the numeral 1 designates the spring plank of a railway truck, the same being a conventional part of the truck equipment which may vary in form and in disposal. The numeral 2 designates the strut of a trussed brake beam, the compression member 4 of which and the tension member 5 of which are shown in section. The strut member 2 supports the floating brake lever 6 in the customary fashion.

Mounted on the spring plank 1 in association with the brake is a supporting member 7, the same extending below the brake beam to provide a safety device which will sustain the brake beam and prevent its falling to the track in the event of its detachment from the hangers which constitute its normal supporting means. The supporting member 7 carries a guide member 8 which is flexible, and upon which is adapted to travel a shoe 9 which is carried by a portion of the brake beam. These parts constitute elements of a sliding third or fourth point support for the brake beam, the purpose of which is to give the brake heads proper guidance to bring the shoes into accurate co-operation with the wheels, all as described in my patent before mentioned. Formed in conjunction with the guide member 8, or supported on the spring plank in conjunction with the supporting member 7 is an upper guard member 10 which extends across a portion of the brake beam above the same. It is suitably spaced away from the brake beam to afford the latter the proper extent and degree of movement necessary in the application and removal of the brakes in the braking operation. An essential of its construction and disposal, however, is that it be so located as to make contact with a portion of the brake beam to limit the upward movement thereof so that, in the event of the loosening or detachment of the brake beam from its normal supporting means, it will be retained against upsetting, or against climbing or moving upwardly under the influence of friction from the revolving wheels on its own inertia when the movement of the truck is varied.

In the construction shown in Fig. 1, the upper guard member is formed by an extension of the rearward portion of the guide member 8. In the modification illustrated in Fig. 2, the upper guard member 10 is 100 105 110

formed as a separate member, and is attached to the spring plank directly. In the forms illustrated in Figs. 3 and 4, the upper guard members are adapted to be employed either in conjunction with the third or fourth point supporting arrangement above described, or independently thereof, it being understood that a fourth point guide member may be carried on the supporting member 7 in coöperation with a fourth point supporting shoe carried on the tension member of the brake beam, or the guide member may be omitted or supplied in the form of an overhung support, the supporting member 7 being utilized to form a lower safety guard. If desired, the upper guard member 10 in such arrangements as those illustrated, may be made of spring metal and disposed so that the brake beam will make contact therewith just prior to the limit of the braking movement of the beam, so that said spring member will be placed under tension when the brakes are applied. Then, upon release of the brakes, the reaction of the spring member will assist in the throw-off, so as to completely remove the brake shoes from contact with the wheels.

From the foregoing description of my invention, it will be seen that it provides a very simple and economical guard member which may be incorporated in a variety of conventional truck structures in conjunction with various well known forms of equipment, and that it will coöperate with various portions thereof, such as the lower safety support, to contribute materially to the sta-

bility, effectiveness and safety of the brake gear.

While I have shown a variety of forms in which the invention may be embodied, I am aware that it is susceptible of still further modification and variation, and that it is not limited to use in conjunction with the illustrative form of brake beam herein shown. Accordingly, it is my intention that the appended claims comprehend all structural modifications and arrangements within the proper scope of the invention.

What I claim is:

1. In a brake rigging including a brake beam, a rigid safety bar member, and a yielding resilient member secured thereto and arranged under the beam, said yielding resilient member being designed to guide the beam in its movement, and an upper guard member arranged above a part of the beam to prevent undue excess vertical movement of the beam.

2. In a truck rigging including a brake beam and a spring plank disposed in association therewith, a resilient upper guard member supported by the spring plank in position to limit upward movement of the beam and to be placed under tension upon braking movement of the same.

In testimony whereof I hereunto affix my signature this 20th day of June, 1917.

CHARLES HAINES WILLIAMS.
